United States Patent Office.

GEORGE M. VAN BUREN, OF NEW YORK, N. Y.

Letters Patent No. 98,448, dated December 28, 1869.

IMPROVEMENT IN TICKET-HOLDERS.

The Schedule referred to in these Letters Patent and making part of the same.

To all whom it may concern:

Be it known that I, GEORGE M. VAN BUREN, of the city of New York, county, and State of New York, have invented a new and useful Improvement in Railroad Ticket-Boxes; and I do hereby declare that the following is a full, clear, and exact description thereof, reference being had to the accompanying drawing, making part of this specification, in which—

Figure 1 is a front view.

Figure 2 is a section of fig. 1.

The nature of this invention consists in the manner of constructing the upper end or opening of the box, so that while the tickets are retained in the receptacle by the top or lid, yet the front ticket may be exposed to view, and the top be easily opened to draw out the ticket when wanted for use.

The box is made with a partition in the middle, and alike at both ends, and can be used for different railroads, ferries, &c.

This box or ticket-holder may be made of any ornamental form, and of suitable metal, *papier-mâché*, vulcanite, or any of the materials used for card-boxes, &c.

In the drawing—

A is the body of the box, having receptacles A¹ A², open at the ends.

B is the lid, and a is the opening on the side, near the end, of sufficient depth to show the card, and yet not deep enough to allow it to fall out. This opening need not extend across the box at the bottom part, but may be in a curved line, or waved, or in any other shape, as the intention is to permit the particular color or distinctive characteristics of the cards or tickets to be seen at a glance, as well as to afford an easy access

of the fingers to lift up the lid, at the same time that the finger gently removes the front card.

b is a partition which divides the box into two apartments. This partition is placed in an oblique or diagonal position, as shown, so that the edges of the contained cards tend to arrange themselves upon this oblique bottom in the form of steps, each card being a little higher than the one immediately behind it, an arrangement which greatly facilitates the taking hold and withdrawing a single card without disturbing or removing any of the others.

Many persons travelling on city passenger-railways, and thence to other routes, either stages, steamers, ferries, and general railroads leading out of the cities, experience inconvenience in readily getting at their tickets. By this simple arrangement their tickets may be placed each in its proper receptacle, and at a glance the proper ticket can be recognized and readily removed.

Having thus fully described my invention, I do not claim the use of a box ticket-holder with a lid, as visiting-cards, and many others, are thus held; but

What I do claim as my invention, and desire to secure by Letters Patent of the United States, is—

A ticket-holder, constructed with a portion of one side at the end left off, whereby the contents may be seen, in connection with the covering-lid B, and diagonal division-plate b, substantially as and for the purpose described.

GEORGE M. VAN BUREN.
